UNITED STATES PATENT OFFICE.

LEWIS F. FILLOON, OF CEDAR RAPIDS, IOWA, ASSIGNEE TO THE CLEFTON COMPANY,
OF OWATONNA, MINNESOTA, A CORPORATION OF MINNESOTA.

ACETYLENE-GAS GENERATOR.

987,055.

Specification of Letters Patent. Patented Mar. 14, 1911.

Application filed November 1, 1910. Serial No. 590,200.

To all whom it may concern:

Be it known that I, LEWIS F. FILLOON, citizen of the United States, residing at Cedar Rapids, in the county of Linn and State of Iowa, have invented certain new and useful Improvements in Acetylene-Gas Generators, of which the following is a specification.

This invention relates to improvements in acetylene gas generators, and has for one of its objects to provide a simply constructed apparatus of this character which may be installed externally of a building and in position to be protected from the frost where- 15 by all danger of the escape of gas is avoided.

Another object of the invention is to provide a device of this character which is automatic in its operation, so that the gas is generated only so fast as used and the 20 amount generated increased with any increase in demand.

Another object of the invention is to provide a device of this character which is readily accessible for inspection or repairs, 25 or for charging with a fresh supply of carbid.

Another object of the invention is to provide a device of this character so arranged that in event of explosion the parts are 30 simply separated without necessarily producing serious damage thereto.

Another object of the invention is to provide a device of this character wherein means are provided for condensing the moisture 35 from the gas to remove surplus moisture prior to its discharge.

Another object of the invention is to provide a device of this character having means for removing surplus moisture from the gas 40 prior to its passage to a purifier.

Another object of the invention is to provide a device of this character having means for internal and external condensation and with a purifier located between the two condensing devices.

With these and other objects in view the invention consists in certain novel features of construction as hereafter shown and described and then specifically pointed out in 50 the claims; and, in the drawings illustrative

of the preferred embodiment of the invention, Figure 1 is a vertical longitudinal section of the improved apparatus; Fig. 2 is a transverse section on the line 2—2 of Fig. 1, looking in the direction of the arrow.

Corresponding and like parts are referred to in the following description and indicated in all the views of the drawings by the same reference characters.

The improved apparatus comprises an outer shell 10, preferably circular and adapted to be embedded for nearly its entire length in the ground, and preferably located externally of the building which is to be lighted. The shell is provided with a detachable closure 11, preferably of sufficient weight to be retained in position without fastening means, so that in the event of explosion the closure will be merely blown off without damaging the apparatus, as herein-after more fully explained. The shell 10 is of sufficient depth to contain a supply of water sufficient to produce the requisite generation of the carbid, and will vary in size according to the number of lights which it is required to furnish gas for, and to locate the water below the frost line. Under ordinary conditions the shell will be about seven feet deep and the water will stand ordinarily at a depth of about three feet in the shell, but these dimensions may be varied as required and as circumstances may warrant, and it is not desired to limit the device to any specific size of the shell or other parts.

Located within the shell 10 is an annular member 12 which is formed smaller in diameter than the shell and with an outwardly flaring bottom portion 13 connected to the shell at a considerable distance above its bottom. By this arrangement an annular space is left between the members 10 and 12, and movably disposed within this space is the downwardly depending portion of a gasometer bell 14 of the usual construction. The member 12 is provided with suitable perforations in its lower part to permit the water to freely pass into the space between the members 10 and 12 and thus form a seal for the gasometer, as will be obvious. The water in the space between the members 10 100

and 12 also forms an effectual means for condensing the moisture from the gas, as hereinafter explained. The member 12 is also provided at its upper edge with numerous orifices or apertures 15 to permit the gas to freely pass into the gasometer bell.

Mounted upon the member 12 is a carbide holder, represented as a whole at 16, and preferably formed with a hopper shaped bottom 17 and a downwardly facing discharge opening 18 at the bottom of the hopper like portion. The member 16 is also provided with a filling opening covered by a suitable cap 19, preferably threaded, and provided with a suitable packing.

The gasometer 14 is provided with suitable lifting handles 20, and a discharge valve 21 is likewise connected to the gasometer to permit the gas to be blown off when required.

Extending through the holder 16 is a tubular bearing 22, through which a vertical shaft 23 extends, and is mounted for rotation in the holder. At its upper end the shaft 23 is provided with a bevel pinion 24 and provided with a valve 25 at its lower end operating to close the discharge 18 of the holder when in one position and to open the discharge when in another position.

Mounted for oscillation upon the holder 30 is a gear segment 26 in constant engagement with the pinion 24 and provided with a weight 27 at one end and a bearing roller 28 at the other end. The weight 27 of the gear segment operates to maintain the segment 35 normally in one position with the valve 25 closed, and when in this position the roller 28 is in its highest position and adapted to be engaged by the top of the gasometer 14 when the latter descends to a point near its 40 lowest position. By this simple arrangement when a sufficient quantity of gas has been generated to elevate the bell 14 the weight 27 maintains the valve 25 in closed position, and cuts off any flow of the carbide. When 45 the consumption of the carbide reduces the quantity to a certain predetermined amount the descent of the bell caused by the consumption of the gas will engage the roller 28 and oscillate the segment 26 with the result of correspondingly oscillating the shaft 23 and opening the valve 25 and permitting a quantity of the carbide to fall into the water below, the latter being indicated at 50 29. This results in the generation of a fresh supply of gas which, rising through the orifices 15, fills the bell 14 and again elevates the latter and thus releases the segment 26 and permits the weight 27 to again close the valve 25 and automatically cut off the 55 further supply of carbide. The improved apparatus is thus automatic in its action, and the gas is generated only so fast as required, or as fast as it is consumed.

Located within the generating chamber,

or internally of the member 12, is a cylindrical member 30 having a downwardly directed inlet 31 and connected at 32 with the main service pipe 33. The member 30 is filled with a suitable purifying material, such as hair, felt, or the like, so that the gas is purified before its passage to the service pipe. At the lower end of the service pipe an extension 34 is located and forms an outside condensing chamber to receive any moisture which results from the condensation of the moisture in the gas or the "sweating" of the pipe. By this means a double condensing action takes place and thereby materially increases the efficiency and utility of the improved apparatus.

The service pipe 33 is conducted into the building to be lighted, preferably beneath the ground as indicated, and is provided with a screw cap which may be removed to provide access to the pipe to enable surplus water to be removed, and prevent flooding of the service pipe.

The improved device is simple in construction, can be inexpensively manufactured of any suitable material, but will preferably be 90 of sheet steel throughout, and also preferably galvanized or otherwise treated to prevent corrosion.

Located within the holder 16, above the discharge 18, is a conical deflector 36 to hold the carbide back and prevent it from clogging and thus checking the discharge.

The lower end of the shaft 23 is threaded and supplied with binding nuts 37 by which the valve 25 is adjustably coupled to the 100 shaft.

Depending from the conical bottom 17 of the holder is a cylindrical shield 39 which serves to protect the valve 25 when the carbide holder is removed.

Having thus described my invention, what is claimed as new is:

1. The combination with a generating tank and a gasometer, of a carbide holder having a discharge opening, a rotating shaft, a valve connected to said shaft and operating as a movable closure to said holder opening, a gear pinion carried by said shaft, and a weighted gear segment engaging said pinion and extending at one end into the path of said gasometer and maintaining said valve normally closed and operated by the gasometer when the latter moves downwardly.

2. The combination with a generating tank and a gasometer, of a carbide holder having a discharge opening, the carbide holder being provided with a vertically disposed tubular bearing extending therethrough from top to bottom and to one side of said discharge opening, a shaft journaled in said tubular bearing to rotate about its longitudinal axis, a closure for the opening connected to the lower end of said shaft and

movable thereby away from the discharge opening in a plane at right angles to the movement of the gasometer, a bevel pinion secured to the upper end of the shaft, and a 5 segment automatically movable in one direction and adapted to be engaged by the gasometer upon the downward movement of the latter to move the segment in the oppo-

site direction, said segment meshing with said pinion.

In testimony whereof, I affix my signature in presence of two witnesses.
